UNITED STATES PATENT OFFICE.

CHARLES A. PAYNE, OF ST. PAUL, MINNESOTA.

SHARPENER FOR KNIVES OR SCISSORS.

SPECIFICATION forming part of Letters Patent No. 691,171, dated January 14, 1902.

Application filed October 23, 1901. Serial No. 79,619. (No model.)

To all whom it may concern:

Be it known that I, CHARLES A. PAYNE, a citizen of the United States, and a resident of St. Paul, in the county of Ramsey and State 5 of Minnesota, have invented a new and Improved Sharpener for Knives or Scissors, of which the following is a full, clear, and exact description.

This invention relates to a class of sharpening devices used to renew the cutting edges of knives and scissors and embodying blades set at an angle to each other, so as to dispose the scraping edges of said blades for engagement with the sides of a knife-blade or of 15 scissors-blades to sharpen the edge of such blades.

The object of my invention is to provide novel details of construction for a sharpening device of the character indicated which 20 adapt it for very effective service and afford a compact, durable, and inexpensive implement equally available for sharpening the cutting edges of knives of different styles and for renewing the cutting edges of the blades 25 of large or small scissors.

The invention consists in the novel construction and combination of parts, as hereinafter described, and defined in the appended claims.

30 Reference is to be had to the accompanying drawings, forming a part of this specification, in which similar characters of reference indicate corresponding parts in all the figures.

Figure 1 is an end view of the sharpening device. Fig. 2 is a plan view of the same. Fig. 3 is a sectional view substantially on the line 3-3 in Fig. 2, and Fig. 4 is a plan view of one of the details which is a feature of the invention.

35 The improvement, in brief, consists of a flat cutter-plate having spaced blades at opposite sides, a flat guide-plate having fingers on opposite edges that may be disposed opposite the spaces between the cutter-blades, the 40 guide-fingers being arranged to afford slots for the introduction of a knife-blade to be sharpened, means to connect these plates and hold them positioned for service as a knife-sharpener, and a scissors-sharpener formed 45 on like ends of the cutter-plate and guide-plate, as will hereinafter be described.

The cutter-plate 10 is formed of a substan-

tially rectangular flat steel planchet having greater length than width. Each side edge of the cutter-plate 10 is slotted oppositely at 55 spaced intervals, these slots having proper depth and width to provide a plurality of spaced blades 11 at each side of the cutter-plate.

The side edges of all the cutter-blades 11 60 are straight and parallel with each other, and sharp corners are produced along said side edges, adapted by properly hardening the cutter-plate 10 to shave metal, the end corners of each blade being slightly rounded, as 65 shown in Fig. 2.

The guide-plate 12 is in oblong form and comprises a flat sheet-metal piece of suitable thickness, either soft steel or wrought-iron being employed. The side edges of the guide-plate 12 are notched oppositely and at spaced intervals, as clearly shown in Fig. 4, these notches *a* having such width as to slightly exceed the breadth of the cutter-blades 11 and preferably have level bottoms *a'*, as shown 75 in Fig. 4. The notching of the guide-plate 12 permits a plurality of guide-fingers 13 to remain intact with the main portion of the guide-plate, and, as shown, these fingers are 80 so spaced apart as to permit each finger to be disposed opposite a space between two of the cutter-blades 11.

The ends of the guide-fingers 13 are preferably rounded, and the side edges of the fingers are sloped to a point *a*² near the level 85 bottom edges *a'* of the notches *a*. From the points *a*² the short remaining portions of the side edges of the guide-fingers 13 are formed parallel with each other and at right angles with the bottoms *a'* of the notches *a*. 90

Preferably the width of the fingers 13 near their bases—that is to say, between the parallel portions of their edges—is slightly less than that of the corresponding spaces between the cutter-blades 11, so that minute 95 crevices *b* will be formed between these edge portions of the fingers and the base portions of the blades 11 when the cutter-plate and guide-plate are secured together, as at 14.

The free ends of the guide-fingers 13 are 100 preferably formed of different widths along one side of the sharpening device, which will obviously change the degree of sloping inclination given to the main portions of the

side edges thereon, and thus afford V-shaped slots *c*, the sides of which have different degrees of angular divergence.

It will be seen that by providing differently-shaped slots *c* the device is well adapted to receive in said slots knife-blades which vary in thickness to sharpen their cutting edges, as will be further explained.

A bracket-support is provided for the combined plates 10 12 and consists of two arms 15, that may be formed on a connecting member 15^a, the latter having such length as will separate the arms a distance nearly equal with the length of said plates, and the member 15^a may be secured upon the guide-plate 12 by the same fastening devices 14 that hold the cutter-plate and guide-plate together.

The spaced arms 15 have their free ends cut into V shape, so that the plates 10 12 may be held inclined from a table-top A or the like if the sharpening device is seated thereon, as shown in Fig. 1.

The scissors-sharpening device, which may also be used as a knife-blade sharpener, is formed at one end of the cutter-plate 10 and guide-plate 12, as follows:

The cutter-plate 10 has a projecting tongue *d*, formed at the center on one or both ends, said tongue having parallel side edges *d'*, that terminate, respectively, at their inner ends in the bottom edges of like notches *d*², formed at each side of the tongue. From the outer ends of the notches *d*² the exterior side edges of the outermost blades 11 are slightly inclined outward to the free ends of said blades, as shown at *d*³ in Fig. 2. At a corresponding end of the guide-plate 12, which projects beyond the nearest pair of guide-fingers 13, a tongue *e*, the counterpart of the tongue *d*, is formed at the center of the guide-plate, and when the cutter-plate 10 and guide-plate 12 are secured together these tongues conform at their edges *e' d'*.

The side edges *e'* of the tongue *e* at their inner ends terminate in the similar-sloped edge portions *e*², that define the end wall of the guide-plate at each side of the tongue, as clearly shown in Fig. 4, and when the plates 10 12 are joined together by the fastening devices 14 the sloped edge portions *e*² register with the slopes *d*³ on the end of the cutter-plate 10.

In using the sharpening implement for renewing the cutting edges of table-knives, 55 carving-knives, or such knives as are employed for domestic purposes the device is placed on a suitable level support, such as a table-top A, near an edge A' of the same, so that the upper edge of the sharpener will incline toward said edge of the table.

The user of the implement holds the device firmly with one hand and with the knife in the other hand applies the cutting edge of the knife-blade to the sharpener by introducing it into an appropriate slot *c* at the heel of the knife-blade and with proper pressure downward draws the blade through the slot.

It will be seen that the inclined edge of the guide-finger 13, engaged with one side of the knife-blade, will press the opposite side of the knife-blade at its edge forcibly against the sharp corner on the blade 11, forming the other edge of the slot engaged by the knife-blade.

The pulling of and downward pressure on the knife-blade will cause the material at the edge thereof to be shaved away, so as to render this edge sharp after one or two passages of the knife-blade through the slot, and it will be seen that the crevice *b* at the bottom of the V-shaped slot *c* will prevent the cutting edge from being dulled by an impinge upon either plate.

The cutting edge of the knife-blade may be completed by passing it through an adjacent slot, wherein the opposite side of the knife-blade will be caused to have contact with an edge of a cutter-blade 11, so that the knife-blade edge will be rendered smooth and sharp by a few moments' use of the implement.

The provision of a soft-metal guide-plate to coact with the cutting-plate adapts the fingers on the guide-plate to serve as a means for holding and guiding the knife-blade into engagement with the sharp edges of the cutting-blades 11 and avoids cutting action on the side of the knife-blade engaged therewith. This provision and the provision of the crevices *b* render the improved implement very efficient in operation.

The different widths afforded some of the slots *c* facilitate the sharpening of knife-blades that are tapered from back to cutting edge, have different thicknesses, and in some cases have their cutting edges formed by beveling one side of the knife-blade at its edges. As in all such different forms for knife-blades, the improved sharpener is adapted to receive the blade of the knife and permit its edge to be effectively pressed into engagement with the scraping edge on a cutter-blade 11 if an appropriate slot *c* is occupied by the knife-blade.

In using the implement as a scissors-sharpener a blade of the scissors is seated on an appropriate cutting edge of the tongue *d* at the heel of the scissors-blade, thus impinging the bevel cutting edge of the scissors-blade upon the tongue, while the side face of the scissors-blade is held in contact with the sloped edge *d*³ of an engaged cutter-blade 11. The scissors-blade is now successively drawn from heel to point over the tongue *d*, so as to forcibly engage the sharp corner thereon, which will scrape sufficient material from the scissors-blade for effective renewal of the cutting edge of the blade thus operated upon.

After one blade of the scissors has been sharpened the implement is reversed in position, so as to dispose the opposite side edge of the tongue *d* uppermost, which will present an appropriate sharp corner thereon for engagement with the other blade of the scis-

sors, which should be drawn across said cor- | ferent sizes between corresponding edges of
